(57) **CLAIM**

The ornamental design for a corner post for a suspended ceiling system, as shown and described.

DESCRIPTION

FIG. 1 is an isometric view of a corner post for a suspended ceiling system.

FIG. 2 is a side view of the corner post for a suspended ceiling system of FIG. 1.

FIG. 3 is another side view of the corner post for a suspended ceiling system of FIG. 1.

FIG. 4 is another side view of the corner post for a suspended ceiling system of FIG. 1.

FIG. 5 is another side view of the corner post for a suspended ceiling system of FIG. 1.

FIG. 6 is a top view of the corner post for a suspended ceiling system of FIG. 1.

FIG. 7 is a bottom view of the corner post for a suspended ceiling system of FIG. 1; and,

FIG. 8 is an isometric view of the corner post for a suspended ceiling system of FIG. 1 incorporated into a taller component.

The dash-dash broken lines in the drawings depict unclaimed portions of the corner post for a suspended ceiling system and form no part of the claimed design. The dash-dot-dash broken lines in the drawings depict unclaimed boundaries that form no part of the claimed design.

1 Claim, 8 Drawing Sheets
